UNITED STATES PATENT OFFICE.

JOSEPH F. ROSS, OF CHICAGO, ILLINOIS.

STEAM BOILER.

Application filed March 31, 1923. Serial No. 629,014.

This invention relates to a boiler of that type designed to furnish steam.

It is an object of this invention to provide an exceedingly economical and cheap construction with an accompanying large radiating surface or area.

With these and other objects in view, which will become more apparent in the following description and disclosures, this invention comprises the novel structure and combinations hereinafter described and more particularly pointed out and defined in the appended claim.

In the accompanying drawings, which illustrate a preferred embodiment of this invention and in which similar reference numerals refer to similar features in the different views:

Figure 1 is a front elevational view of the boiler.

Figure 2 is a top plan view thereof.

Figure 3 is an enlarged section upon the line 3—3 of Figure 1.

Figure 4 is an enlarged section upon the line 4—4 of Figure 3.

Figure 5 is an enlarged section upon the line 5—5 of Figure 3.

Figure 6 is an enlarged section upon the line 6—6 of Figure 3.

In referring now to the different figures of the drawings, it will be observed that the lateral sides and top of the boiler are formed by a single sheet metal plate member 1 which is stamped into substantially a U-shaped form. Within the metal plate member 1, there is another stamped sheet metal form 2 having lower parallel sides which are spaced from the sides of the member 1 to define a fluid partition or chamber therebetween. Above the fire box, these parallel sides merge into short horizontal portions 2^a which in turn merge into a U-shaped portion 2^b which constitutes part of the flue. The lower ends of the parallel sides of the member 2 are provided with horizontal flanges 2^c that extend to the sides of the outer member 1 to which they are welded, and they rest upon ledges 3 integral with the side base member 4. Spacing bolts 5 hold the members 1 and 2 in rigid relation and add strength to the structure.

The rear end of the outer metal form 1 is closed by an end plate 6 (Figure 3) and the rear end of the inner metal form 2 is closed by a metal plate 7 welded thereto which is suitably spaced from the plate 6 to define a

fluid partition or chamber therebetween; the lower end being provided with a horizontal flange 8 that is preferably welded to the bottom of the plates 6 and rests upon a ledge 9 of the rear base member 10. The lower portion of the plates 6 and 7 are preferably connected by the spacing bolts 5 to maintain the same in rigid spaced relation. The upper ends of the plates 6 and 7 are respectively welded to the outer and inner forms 1 and 2. A cylindrical exhaust box 11^a is welded to the upper rear end of the outer form 1 from which the smoke or exhaust pipe 12 extends.

In referring to Figure 4, it will be observed that the space between the upper half of the outer metal form 1 and the upper part 2^b of the metal form 2 is in the form of a horse shoe which is closed at the front by a plate member 11 which is welded between said members 1 and 2 and the whole front upper part is closed by a metal box-like structure 12' forming a box, the same being welded to the outer member 1 and having a door 13 for inspection of the flue. Metal strips, such as 14 or the angle irons 15, may be used as welded splices at the joints to produce a rigid construction.

The front end of the fire box is formed by a door 16 surrounded by a fluid chamber. This fluid chamber is formed by welding a metal plate 17 to the front ends of the inner member 2 along the lateral margins thereof as shown in Figure 6 and providing said plate with an opening corresponding to the door and with outwardly extending flanges 17^a and 17^b which respectively form the sides, top and bottom of the doorway. The lower margin of the plate 17 is provided with a right-angled flange 18 welded to the ledge of the front base member 10 and the upper margin of said plate is provided with a similar flange 18 that extends outwardly and is welded to the plate member 11 as shown in Figure 3. A plate member 19 having an aperture corresponding to the opening formed by the flanges 17^a and 17^b and comprising an extension of the plate 11, if desired, is welded at its lateral edges to the outer member 1 as shown in Figure 6 and is also welded at its upper and lower edges to the outer margins of flanges 18 of the inner plate 17. Likewise, the border of the opening in the plate member 19 is welded to the flanges 17^a and 17^b of the inner member 2, and spacing bolts 5 may ex-

tend through the plates 17 and 19 for strengthening the structure. The plates 17 and 19 are sufficiently spaced to provide a fluid chamber therebetween.

- 5 A series of fluid pipes 20 are supported by the plate members 7 and 17 and communicate with the front and rear parts of the fluid chamber or partition that surrounds the fire box. The fluid is not only intended
10 to fill the partition around the fire box, but it is also intended to extend sufficiently above the fire box to surround the flue 2^b and the different series of flue pipes 21 which are supported by the horse shoe plate
15 11 and the plate 6 as shown in Figure 5. Bolts 22 preferably extend between the outer form 1 and the flue 2^b for adding strength to the structure.

In referring to Figure 4, it will be noted
20 that the flue 2^b is open at its lower end and communicates directly with the fire box. It is, however, closed by a baffle 23 formed of fire brick except for a short space 24 (Figure 3) at the rear.

25 It will therefore be necessary for the flames to pass to the rear of the fire box, then through the opening 24, and through the flue 2^b and into the flue 12^a from which they may escape through the flue tubes 21 into the rear flue box 11^a. The steam may be led off through the pipe 25. It will therefore be evident that the fluid is subjected to a large heating area through the backward and forward movement of the flames or heated air.

Proper plugs such as 26, whereby the fluid pipes and chamber may be inspected and cleaned, may be provided. In the present exemplification of this invention, the grate
40 27 is suitably supported at the base of the fire box and the base members 4 may form the usual ash compartment.

It is characteristic of the boiler constructed according to this invention that the different parts can be readily stamped from

suitable sheet metal and can be quickly assembled by welding, whereby the labor and cost is greatly reduced.

It should also be noted that the portion 2^b is extended outwardly and is welded to 50 the plate 11, the bottom of said projecting portion being closed by the flange 18 which is welded to the plate 19. This construction affords a water space above the fire box 55 and at the same time, the shape of said member 2^b allows it to form the upper part of the combustion chamber. If desired, the inner form 2 may be made in sections secured together by welding at suitable points. 60

I am aware that numerous details of construction may be varied through a wide range without departing from the principles of this invention, and I, therefore do not purpose limiting the patent granted, otherwise than necessitated by the prior art. 65

I claim as my invention:

In a boiler, an outer metal shell, an inner metal shell having a lower fire box portion and an upper reduced flue chamber extending from the rear end of the inner shell to the forward end of the outer shell, the walls of said shells being spaced apart to provide a fluid chamber, a series of fluid pipes disposed in a horizontal row in the top of said fire box and communicating with said fluid chamber at front and rear, a baffle supported by said fluid pipes between said fire box and flue chamber and permitting communication therebetween at the rear only, 70 flue pipes supported by the outer shell and positioned between the reduced flue chamber and the sides of the outer shell, a flue box secured to the outer shell and establishing communication between said flue chamber 75 and said flue pipes, and an exhaust box at the rear into which said flue pipes discharge. 80

In testimony whereof I have hereunto subscribed my name.

JOSEPH F. ROSS.
